HOSPITAL BED

Lewis E. Davis, Newport News, Va.

Application August 9, 1941, Serial No. 406,195

6 Claims. (Cl. 5—69)

This invention relates to a hospital bed, and it is an object of the invention to provide a bed of this kind so constructed to allow a patient to be readily supported in such different postures as may be desired.

Another object of the invention is to provide a bed of this kind having a bed bottom or spring constructed in a manner to include a leg supporting section with means associated therewith whereby said leg supporting section can be conveniently lowered as desired from the horizontal, or returned to the horizontal, and furthermore wherein said leg section when fully lowered provides means for supporting the foot portion of the bed when the foot piece is removed.

An additional object of the invention is to provide a hospital bed embodying a bed bottom or spring comprising pivotally connected sections, together with means for independently operating certain of the sections to enable a ready and convenient change in the posture of the patient occupying the bed.

The invention has for a still further object to provide a bed of this kind including a bed bottom or spring having a vertically swinging leg supporting section, said leg supporting section providing means whereby the bed structure can be readily supported in the fashion of a chair after the foot piece has been removed and to enable the patient to readily leave the bed or return thereto, the extending portions of the side rail of the bed, when the leg supporting section is lowered, serving as guide rails to facilitate the movement of the patient.

An additional object of the invention is to provide a hospital bed wherein one of the end pieces, and preferably the head piece, is provided with means for supporting the necessary equipment to be utilized for irrigation and intravenous treatments.

A still further object of the invention is to provide a hospital bed including an adjustable bed bottom or spring to allow the desired changing of the postures of the patient, together with arm rests supported in such positions to be conveniently used by the patient when the head section of the bed bottom or spring is sufficiently raised.

The invention also relates to a hospital bed having its bed bottom or spring provided with a swinging foot supporting section, together with means carried by the foot piece of the bed serving as a foot support when the foot supporting section of the bed bottom or spring is lowered.

The invention consists in the details of con-

struction and in the combination and arrangement of the several parts of my improved hospital bed whereby certain important advantages are attained, as will be hereinafter more fully set forth.

In order that my invention may be the better understood, I will now proceed to describe the same with reference to the accompanying drawings, wherein—

- 10 Figure 1 is a view in side elevation, with portions broken away, of a hospital bed constructed in accordance with an embodiment of my invention, second positions of certain of the parts being indicated by broken lines;
- 15 Figure 2 is a view in top plan of the bed as illustrated in Figure 1, with certain of the parts in section and the bed bottom or spring omitted; Figure 3 is an enlarged fragmentary sectional view taken substantially on the line 3—3 of Figure 2;
- 20 Figure 4 is an enlarged fragmentary sectional view taken substantially on the line 4—4 of Figure 2;
- 25 Figure 5 is a detailed sectional view taken substantially on the line 5—5 of Figure 1;
- 30 Figure 6 is a fragmentary sectional view illustrating the hand rest partly folded;
- 35 Figure 7 is a detailed view, partly in top plan and partly in section, illustrating the foot support as herein embodied;
- 40 Figure 8 is an enlarged fragmentary sectional view taken substantially on the line 8—8 of Figure 2, with certain of the parts in a second position;
- 45 Figure 9 is a view in top plan of the bed bottom or spring as herein comprised unapplied, the spring fabric being in fragment;
- 50 Figure 10 is a detailed sectional view taken substantially on the line 10—10 of Figure 9;
- 55 Figure 11 is a view in top plan showing both of the table leaves in assembled relation across the bed;
- 60 Figure 12 is a view in side elevation of a bed constructed in accordance with another embodiment of my invention;
- 65 Figure 13 is a fragmentary view, partly in section and partly in elevation, showing the means for operating the drive shaft as comprised in the second embodiment of the invention, the line of section being taken substantially on the line 13—13 of Figure 12;
- 70 Figure 14 is a fragmentary view, partly in section and partly in elevation, illustrating the means for operating one of the rock shafts from the drive shaft; and

Figure 15 is a horizontal sectional view taken substantially on the line 15—15 of Figure 14.

In the embodiment of my invention as illustrated in Figures 1 to 8 of the drawings, the bed comprises a head piece H, a foot piece F and the side rails R. These parts may be as preferred, it only being necessary to particularly point out that the foot piece F is to be readily applied or removed and that the head piece H includes the corner posts 1, each of which having its upper portion hollow and open at the top of the post. The bore 2 of the post has suitably fixed therein a member 3 intersecting the bore 2 and provided with a central opening 4 through which freely passes an elongated shank 5. Threading on this shank 5 is a nut 6 for contact from above with the member 3 whereby the shank 5 may be supported with the upper end thereof disposed a desired distance above the top of the post 1. The upper end of this shank 5 carries a hook member 7 to provide means whereby there can be conveniently supported the required equipment for use in connection with irrigation and intravenous treatments. When this hook member 7 is not to be used, the nut 6 can be so adjusted on the shank 5 as to allow the shank 5 and the hook member 7 to be housed within the bore 2 of the post 1, and after which the upper open end of the post is closed by the swinging cap 8 carried by the upper end portion of the post 1, and which cap may be of such design or configuration as preferred.

The side rails R are conventional insofar as pertains to the general construction and mounting thereof, but each of said side rails, however, has its foot portion laterally offset, as at 9, so that in the assembled bed structure the foot portions 10 of the side rails R will be spaced apart a distance greater than the remaining or forward portions of the rails R, as is clearly illustrated in Figure 2 of the drawings. The foot portions 10 have interposed therebetween the transversely disposed bar 11. This bar 11 is suitably secured to the side rails R and provides a pivotal mounting for the side arms 12 of a substantially U-shaped supporting member M. The side arms 12 of this member M are positioned closely and adjacent to the foot portions 10 of the rails R, while the intermediate or cross member 14 of the frame M, when said frame is in a horizontal position, is closely adjacent to the outer ends of the foot portions 10 or to the foot piece F.

Associated with the bed structure is a bed bottom or spring B. This bottom or spring B is adapted to have placed thereon the usual mattress, and said bed bottom or spring comprises a head section having side arms 15, each of which having its inner end portion pivotally connected, as at 16, to the end portion of a side arm 17 of a central section. Each of the side arms 17 of the central section has pivotal connection, as at 18, with a side arm 19 of an upper leg supporting section, and each of the arms 19 is pivotally connected, as at 20, to an end portion of an arm 21 of a lower leg supporting section of the bed bottom or spring. These various sections of the bed bottom or spring are of such sizes as may be preferred or necessitated by practice.

When in horizontal position the side arms 15, 17 and 19 rest from above upon the forward portions of the side rails R while the side arms 21 of the lower leg supporting section rest upon the arms 12 of the frame M with the pivotal

connection between each of the adjacent arms 19 and 21 so positioned with respect to the offset portion 9 of the adjacent side rail R to allow the frame M and the lower leg section of the bed bottom or spring supported thereby to be lowered or raised. The swinging movement of the frame M is entirely below the rails R and the upward movement of the frame M is limited by contact with each of the side rails R of an outstanding stop lug 22 carried by the adjacent arm 12 of the frame M. The contact of the stop lugs 22 with the rails R occurs when the frame M is in its horizontal position or in a position substantially coplanar with the portions 10 of the side rails R.

At a suitable point intermediate their ends the side arms 12 of the frame M are connected by a bar 23 with which is operatively connected the rigid links 24 extending downwardly therefrom. These links 24 are also pivotally connected, as at 25, to the rock arms 26 depending from a shaft 27 extending transversely between the rails R, and each end portion of which is rotatably supported by a bearing bracket 28 depending from a side rail R closely adjacent to, but forwardly of, the offset portion 9 of the side rail. Upon requisite turning of the shaft 27 the frame M, together with the lower leg supporting section of the bed bottom or spring, may be lowered as desired with respect to the side rails R. When the frame M is fully lowered, as indicated by broken lines in Figure 1, said frame M will provide a support for the foot portion of the structure after the foot piece F has been removed. This is of advantage as after the removal of the foot piece F the patient can be more conveniently placed upon or removed from the bed, or more especially when the patient is in such condition as to enable him to assist himself. With the foot piece F removed and the frame M fully lowered to serve as a support, the portions 10 of the side rails R will then serve as effective guides and supports.

When the foot piece is lowered as desired, as illustrated by full lines in Figure 1, it is of advantage to employ a foot rest for the convenience of the patient. As particularly illustrated in Figures 1 and 7 of the drawings, the foot rest comprises a main section or plate 29 of desired width and of a length to extend substantially entirely across the assembled bed structure. This member or plate 29, at its opposite end portions, is provided with the rearwardly directed ears 30 between each pair of which is received an outstanding lug 31 carried by a sleeve 32. The assembled ears 30 and lugs 31 have disposed therethrough the pivot pins 33 on each of which is threaded a clamping nut 34. The nuts 34 provide means whereby the member or plate 29 may be supported in desired position with respect to the lowered frame M. The lower or free portion of the member or plate 29 has telescopically engaging therein an extension plate or member 35 held in its desired selected adjustments with respect to the body or plate 29 by the holding screws 36 threading from below into the body or plate 29 for clamping or holding contact with the extension plate 35. It is believed to be obvious that this extension plate 35 is of importance under those conditions when the frame M is lowered to a position materially below the lower margin of the member or plate 29.

Depending from each of the side rails R, pref-

erably below the pivotal connection 18 of the adjacent side arms 17 and 19, is a bearing plate 36' which provides a mounting for an end portion of a rock shaft 37 which extends transversely across the bed structure. This shaft 37 is provided with the forwardly and downwardly disposed rock arms 38, the lower end portions of which being pivotally connected, as at 39, to the lower end portions of the rigid links 40. Each of these links 40 has its upper end portion pivotally connected to a rod 41 connecting the side arms 19 so that upon requisite rocking of the shaft 37 the upper leg supporting section of the bed bottom or spring will be raised or lowered. Upon the raising of the upper leg supporting section, the frame M is at its limit of upward movement or in position between the portions 10 of the side rails R so that as the arms 19 of the upper leg supporting section move upwardly the outer or free end portions of the arms 21 of the lower leg supporting section will freely ride along the side arms 12 of the frame M so that the upper leg supporting section and the lower leg supporting section may assume a required position, as indicated by broken lines in Figure 1. The shaft 37 also has depending therefrom a rock arm 42 which is pivotally connected, as at 43, to the outer end portion of an elongated rod 44. This rod 44, throughout the major portion of its length, is tubular with its end portion remote from its pivotal connection 43 open. The open end portion of this rod 44 telescopically engages within an elongated sleeve 45 rigidly secured to and extending from a wall 46 of a boxing 47. This boxing 47 is freely mounted on a shaft 48 extending transversely of the bed at the head portion thereof, and each end portion of this shaft 48 is rotatably supported by a bracket 49 depending from a side rail R. One end portion of this shaft 48 is provided with an operating crank 50, or other suitable means whereby the shaft 48 may be rotated in either direction as desired.

Within the boxing 47 the shaft 48 has fixed thereto a pinion 51 in mesh with a gear 52 carried by an end portion of a shaft 53 extending within the boxing 47 through the wall 46. This shaft 53 is of desired length and extends axially through the sleeve 45 and threads through a nut 54 suitably fixed within the open end portion of the rod 44 so that as the shaft 53 rotates the rod 44 will be either extended or retracted to effect the desired rocking movement of the shaft 37 to either raise or lower the leg supporting sections of the bed bottom or spring.

The shaft 27 is provided with the additional rock arm 55 which is disposed downwardly therefrom, and the outer portion of this arm 55 is pivotally connected, as at 56, to an end portion of a tubular rod 57. This rod 57 telescopically engages within an elongated sleeve 58 extending from a wall of a boxing 59 freely mounted on a shaft 60. The shaft 60 is also at the head portion of the bed structure and is provided with an operating crank 61 or the like whereby the shaft 60 may be rotated as required to lower or raise the frame M as desired. The shaft 60 operates to impart desired endwise movement to the rod 57 in the same manner as hereinbefore set forth with respect to the rod 44, and for which reason a more detailed description and illustration is not believed necessary.

Interposed between and connected to the side

arms 15 of the head section of the bed bottom or spring is a rod 62 with which is pivotally connected the upper end portion of the rigid links 63. The lower portion of each of these links 63 is pivotally connected, as at 64, to an end portion of a rock arm 65 carried by a shaft 66 extending transversely of and between the rails R. Each end portion of this shaft 66 is rotatably supported by a bearing 67 depending from the adjacent side rail R. The shaft 66 is provided with a further rock arm 68 depending therefrom and to the lower end portion of which is pivotally connected, as at 69, an end portion of a tubular rod 70 which telescopically engages within a sleeve 71. This sleeve 71 is carried by a wall of a housing 72 freely mounted on a shaft 73, each end portion of which is rotatably supported by a bearing 74 depending from a side rail R. The shaft 73 is provided with a crank 75 or other suitable means for rotating the same to extend or retract the rod 70 to raise or lower, as desired, the head section of the bed bottom or spring. The shaft 73 is operatively engaged with the rod 70 in the same manner as hereinbefore stated with respect to the rod 44.

Interposed between the side rails R at the head portions thereof are the cross members 76 with

said cross members positioned above the shafts 73, 48 and 60. Each of these cross members 76 has depending therefrom the bearings 77 for the shaft immediately therebelow, whereby further support for the shaft is provided and also to assure the desired maintenance upon the shaft of the boxings 59, 41 and 72.

Again referring to the plate or member 29 of the foot rest, it is to be further explained that the sleeves 32 are slidably and snugly mounted on the lower portions of the corner posts 78 of the foot piece F and said sleeves are locked in

desired positions along said posts 78 by a conventional binding screw 79, or the like. This adjustment along the corner posts 78 of the foot piece F further facilitates and assures the proper positioning of the member or plate 29 with respect

to the outer or free end of the frame M when in a lowered position.

The central portion of each of the side rails R, at a location alongside of a side arm 17 of the central section of the bed bottom or springs, has

secured thereto a plate 80. This plate 80, as particularly illustrated in Figures 5 and 6, extends a slight distance below its side rail R, and to the lower marginal portion of this plate 80 is hingedly or pivotally connected, as at 81, the lower or inner

end portions of a pair of substantially parallel elongated posts 82. These posts are maintained in desired assembled relation by the intermediate cross bars 83 interposed between the posts 82 and suitably secured thereto. These posts 82 are fur-

ther connected at their upper extremities by an arm 84 which extends a desired distance beyond the posts 82 in a direction toward the head end of the bed to provide an arm rest or support 85. This arm rest 85 may be upholstered or other-

wise finished as preferred.

Each of the posts 82, as herein disclosed, is

L-shaped in cross section and has a flange a disposed in a direction transversely of the bed. The upper end b of this flange a is disposed on a bevel

of 45 degrees. The portion of the arm 84 be-

tween the posts 82 has hingedly or pivotally con-

nected thereto, as at 86, the supporting members

87 for a table leaf 88. These supports 87 are

provided with depending flanges c, the inner ends

75 of which being connected by a cross strip 89 dis-

posed on a bevel or incline of 45 degrees. This plate 89 is so positioned as to contact with the outer beveled ends b of the posts 82 when the leaf 88 is swung inwardly of the bed to assure said leaf 88 being supported in an effective position across the bed. It is also to be stated that the leaf 88 is preferably of a length approximating one-half the width of the bed structure so that when both of the leaves 88 are in raised or working position a table will be provided substantially entirely across the bed.

When it is not desired to use the leaf 88 the same is swung to a position to overlie the outer sides of the posts 82 and connecting members 83, as illustrated in Figure 6, whereupon the posts 83 will be swung in a position depending from its side rail R so that the leaf 88 and its associated parts will be entirely out of the way.

In the embodiment of the invention as illustrated in Figures 12 to 15 of the accompanying drawings, the general construction of the bed proper and the bed bottom or spring is substantially the same as hereinbefore described in detail with respect to the first embodiment of the invention. In the second form, each of the links 90 pivotally connected with a side arm 91 of a lower leg supporting section, is pivotally connected, as at 92, with a rock arm 93 depending from a shaft 94 bridging the space between the side rails S of the bed structure and suitably supported thereby. The support for the shaft 94 carried by one of the side rails S constitutes a housing 95 and fixed to the shaft 94 within this housing 95 is a worm wheel 96 which meshes with a worm 97 freely mounted on a drive shaft 98 extending lengthwise of the side rail S. One extremity of the worm 97 is formed to provide a clutch face 99 with which coacts a clutch member 100. This clutch member 100 is mounted on the shaft 98 for rotation therewith, but free for movement lengthwise thereof so that the member 100 can be shifted into or out of engagement with the clutch face 99 when desired. This clutch member 100 is positioned within the housing 95 and is provided with a circumferentially disposed continuous groove 101 in which is received the inner end portion of an operating member 102 extending within the housing 95 through a suitably disposed and positioned slot 103. The outer end portion of this operating member 102 is provided with an enlargement or head 104 to allow the clutch member 100 to be manually shifted into clutching or declutching position with respect to the worm 97 as required. Obviously, with the clutch member 100 in clutching engagement with the clutch face 99 of the worm 97, the worm 97 and shaft 98 will rotate in unison. With the member 100 in declutching position the shaft 98 will rotate independently of the worm 97.

The rock shaft 105 for operating the upper leg supporting section is also disposed transversely of the bed structure and operatively supported by the side rails S. One of the supports for the shaft 105 constitutes a housing 106 through which the shaft 98 extends and which shafts 98 and 105 cooperate in the same manner as hereinbefore described with respect to the shafts 94 and 98. The rock shaft 107 for the head section of the bed bottom or spring is also disposed transversely of the bed and rotatably supported by the side rails S, with one of such supports constituting a housing 108 through which the shaft 98 is also directed. This shaft 107 and the shaft 98 have the same operating coaction as hereinbefore set forth with respect to the shaft

94 and the shaft 98. It is, therefore, to be particularly stated at this time that while the shafts 94, 105 and 107 are driven from the common shaft 98, yet each of said shafts can be readily operated independently of the other when so required.

The shaft 98 extends within a housing 109 depending from the head portion of the side rail S carrying the housings 95, 106 and 108. The end portion of the shaft within this housing 109 carries a gear 110 meshing with a gear 111 within the housing 109. This gear 111 is fixed upon a shaft 112 rotatably supported by a side wall of the housing 109 and extending outwardly beyond the housing 109 so that the shaft 112 may be rotated at will and in the required direction by a hand crank 113 or the like.

The intermediate member 14 of the lower leg section has mounted therealong a bumper 114 of rubber compound or other material desired. It is believed to be obvious that a similar member is to be employed in connection with the lower foot section as comprised in the second embodiment of the invention. This member has direct contact with the floor or kindred supporting surface when the member M is in its lowermost position to serve as a support for the foot end of the bed structure after the foot piece F has been removed. This bumper is, therefore, of particular importance to eliminate marring of the surface of the floor or the like, and to also assure the lowered member M having effective contact with the floor surface.

From the foregoing description it is thought to be obvious that a hospital bed constructed in accordance with my invention is particularly well adapted for use by reason of the convenience and facility with which it may be assembled and operated.

I claim:

1. A hospital bed including a head piece, side members, a removable foot piece, the foot portions of the side members being outwardly offset and having their top surfaces coplanar with the top surfaces of the forward portions, and a swinging frame supported between said outwardly offset portions of the side members, said swinging frame having side arms, the side arms of the frame being substantially aligned with the forward portions of the side members and having their top surfaces in the plane of the top surfaces of the said forward and foot portions when the frame is at the limit of its upward swinging movement, the tops of the forward portions of the side members and of the side arms of the swinging frame providing a continuous support lengthwise of the bed for an articulated bed bottom.

2. A hospital bed including a head piece, side members, a removable foot piece, the foot portions of the side members being outwardly offset, a swinging frame supported between said outwardly offset portions of the side members, said swinging frame having side arms, the side arms of the frame being substantially aligned with the forward portions of the side members when the frame is at the limit of its upward swinging movement, the forward portions of the side members and the side arms of the swinging frame providing a continuous support lengthwise of the bed for an articulated bed bottom, and means for raising or lowering the frame and for maintaining said frame in its different adjusted positions, said frame being of a length when in its fully lowered position to contact with an underlying supporting surface for sustaining the foot

end of the bed when the foot piece is removed.

3. A hospital bed including a head piece, side members, a foot piece connected with the side members for complete removal therefrom, the foot portions of the side members being outwardly offset, a swinging frame supported between said outwardly offset portions of the side members, said swinging frame having side arms, the side arms of the frame being substantially aligned with the forward portions of the side members when the frame is at the limit of its upward swinging movement, the forward portions of the side members and the side arms of the swinging frame providing a continuous support lengthwise of the bed for an articulated bed bottom, and means for raising or lowering the frame and for maintaining said frame in its different adjusted positions, said frame being of a length when in its fully lowered position to contact with an underlying supporting surface for sustaining the foot end of the bed when the foot piece is removed, the offset foot portions of the side members constituting freely extending guide arms when the frame is lowered and the foot piece is removed.

4. A hospital bed comprising a head piece, side members connected with the head piece, and a foot piece connected with the side members, a frame supported between the side members at the foot of the bed for oscillation on a horizontal axis, the frame being swingable on said axis from a position coplanar with the side members downwardly to a vertical position, a bed bottom supported upon the side members and upon the frame, the bed bottom comprising a plurality of

hingedly connected sections, one of said sections being designed to support the lower leg and overlying the frame and an adjoining section being designed to support the upper leg, a pair of rock shafts disposed transversely of and supported by the side members, a lever and link connection between one shaft and the frame, a lever and link connection between the other shaft and the upper leg supporting portion of the bed bottom, and mechanism operable from a position adjacent the head piece for selectively imparting rocking motion to said shafts.

5. A hospital bed structure as set forth in claim 4, in which said mechanism includes a 15 gearing unit supported for rocking motion upon an axis extending transversely of the bed, a crank actuated shaft for imparting power through the gear unit, a driven shaft receiving power through the gear unit from the crank actuated shaft and extending longitudinally of the bed, a reciprocating arm extending longitudinally of the bed and having operative connection at one end with a rock shaft, and a screw connection between the other end of the reciprocating arm and the driven shaft for extending and retracting said arm.

6. A hospital bed structure as set forth in claim 4, in which said mechanism comprises a single shaft extending lengthwise of the bed, means for imparting rotary motion to said single shaft, said single shaft passing across said rock shafts, and a clutch controlled means for selectively establishing driving connection between the single shaft and the rock shafts.
